UNITED STATES PATENT OFFICE

JAMES W. PARKER, OF ANN ARBOR TOWNSHIP, WASHTENAW COUNTY, MICHIGAN,
AND JOHN E. BLACK, OF RUMSON, NEW JERSEY; SAID BLACK ASSIGNOR TO THE
BABCOCK & WILCOX COMPANY, OF BAYONNE, NEW JERSEY, A CORPORATION OF NEW
JERSEY

ECONOMIZER

Application filed July 17, 1926. Serial No. 123,067. 03

This invention relates to an economizer that may be located above a steam boiler and will occupy a small space and, at the same time, the waste gases and water to be heated will pass in countercurrent directions through the economizer. The invention will be understood from the description in connection with the accompanying drawings, in which Fig. 1 is a vertical section through an illustrative embodiment of the invention; Fig. 2 is a section along the line 2—2 of Fig. 3; Fig. 3 is a side elevation of the device and Fig. 4 is a section along the line 4—4 of Fig. 3. The invention is illustrated in connection with the upper portion of a boiler of the Stirling type, in which reference character 5 indicates the steam and water drums and 6 indicates tubes connecting the drums. Gases from a furnace (not shown) pass over the tubes of the boiler in the usual manner, becoming cooled thereby to a certain extent, and then the waste gases pass through conduits 7 on opposite sides of the boiler upwardly over walls or baffles 8, each of which forms a side of a channel in which water tubes of the economizer are located. The walls 9 or other sides of the channels into which the waste gases enter extend downwardly, and hoppers 10 are located below the same, and are provided with openings 11 through which soot that has collected in the hoppers may be removed. The hoppers 10 open into adjacent channels, one of the sides of which is formed by the walls 9, these channels being separated by the middle wall 12, and opening into flues or stacks 13 (Fig. 3).

The channels between the walls 8 and 9 through which the waste gases pass downwardly, and also the channels between the walls 9 and 12 through which the gases pass upwardly are provided with vertical rows of headers that are connected by tubes extending transversely of the channels. The inner channels between the walls 9 and 12 are provided on one side with headers 20 disposed one above the other, the top one of these headers being an inlet header for the cold water. Corresponding rows of headers 21 are disposed along the other side of these channels, and tubes 22 extending transversely

along the channels and sloping slightly, as shown in Fig. 3, connect the headers. A header 21' on each side of the wall 12 at the bottom of the rows is sufficiently long to extend across a gas channel between the walls 9 and 12 and the walls 8 and 9. These headers may be provided with drain pipes 21" and the headers serve to lead the water from the gas channels between the walls 9 and 12 to the gas channels between the walls 8 and 9. Vertical rows of headers 23 are installed above one another along the sides of the channels between the walls 8 and 9, and are connected to similar rows of headers 24 along the other side of the channels by means of transversely extending tubes 25. The top-most headers 24' of the rows 24 are the outlet headers for the hot water, and these headers may be provided with outlets 26 for the hot water, as well as water relief valves 27 of the well-known sort.

In the operation of the device, waste gases from the boiler pass through the conduit 7 into the upper portion of the economizer downwardly across the tubes 25, through the hoppers 10 and upwardly across the tubes 22 into the outlets 13. At the same time, cold water is introduced through the headers 20, passes through tubes 22 and the rows of headers along the sides of the economizer through the long headers 21', tubes 25 and rows of headers 23 and 24, and finally through the outlets 26. The water and hot gases are thus caused to flow through the economizer in countercurrent directions and, at the same time, a very compact economizer is provided.

We claim:

1. In combination, a boiler, an outlet flue for the gases, an inner and an outer set of channels located side by side and above said boiler, fluid heaters located in the respective sets of channels, the channels of one set communicating at one end with said outlet flue and at their other ends with the respective channels of the other set, and conduits extending upwardly from opposite sides of said boiler along the outer sides of said channels for conducting gases from the boiler to the opposite ends of the last named channels.

2. In combination, a boiler, an outlet flue

for the gases, two pairs of vertically disposed channels each pair comprising an inner and an outer channel and the channels of each pair being located side by side and above said boiler, 6 economizers located in the respective pairs of channels, the inner channels communicating at one end with said outlet flue and at their other ends with the other channels of the respective pairs, and conduits extending upwardly from opposite sides of said boiler along the outer sides of said channels for conducting gases from the boiler to the opposite ends of the last-named channels.

3. In combination, a boiler, an outlet flue 15 for the gases disposed above said boiler, two pairs of vertically disposed channels, each pair comprising an inner and an outer channel and the channels of each pair being located side by side and above said boiler, economizers located in the respective pairs of channels, the inner channels communicating at their upper ends with said outlet flue and at their lower ends with the other channels of the respective pairs, and conduits extending 20 upwardly from opposite sides of said boiler along the outer sides of said channels for conducting gases to the upper ends of the last-named channels.

4. In combination, a boiler, an outlet flue 30 for the gases disposed above said boiler, two pairs of vertically disposed channels, each pair comprising an inner and an outer channel and the channels of each pair being located side by side and above said boiler, economizers located in the respective pairs of channels, the inner channels communicating at one end with said outlet flue and at their other ends with the other channels of the respective pairs, and conduits extending 35 upwardly from opposite sides of said boiler along the outer sides of said channels for conducting gases to the other ends of the last-named channels and connections providing for the flow of water through the tubes 40 of the economizers countercurrent to the gases.

5. In combination, a boiler, an outlet flue 50 for the gases disposed above the boiler, two pairs of vertically disposed channels, each pair comprising inner and outer channels, the channels of the respective pairs being located side by side and above said boiler, economizers located in the respective pairs of channels, each economizer comprising headers, tubes 55 connecting the headers and extending transversely across said channels, each of the inner channels communicating at one end with said outlet flue and at its other end with one end of the other channel of the respective pair, and conduits extending upwardly from opposite 60 sides of said boiler along the outer sides of said channels for conducting gases to the other end of each of the outer channels.

6. In combination, a boiler, an outlet flue 65 for the gases disposed above the boiler, two

pairs of vertically disposed channels, each pair comprising inner and outer channels, the channels of the respective pairs being located side by side and above said boiler, economizers located in the respective pairs of channels, each economizer comprising headers, tubes connecting the headers and extending transversely across said channels, the inner channels communicating at one end with said outlet flue and at their other ends with the other channels of the respective pairs, and conduits extending upwardly from opposite sides of said boiler along the outer sides of said channels for conducting gases to the upper ends of the last-named channels, 70 and connections providing for the flow of water through the tubes of the economizers in a direction generally counter to the flow of gases thereover.

7. In combination, a boiler, an outlet flue 80 for the gases disposed above the boiler, two pairs of vertically disposed channels, each pair comprising inner and outer channels, the channels of the respective pairs being located side by side and above said boiler, 85 economizers located in the respective pairs of channels, each economizer comprising headers, tubes connecting the headers and extending transversely across said channels, the inner channels communicating at one end with said outlet flue and at their other ends with the ends of the other channels of the respective pairs, and conduits extending upwardly from opposite sides of said boiler along the outer sides of said channels for conducting gases to the upper ends of the last-named channels, one of the headers for each 90 economizer being located at the lower portion thereof and extending completely across an inner and outer channel and affording communication between the portions of the economizer located in the channels of a given pair.

JAMES W. PARKER,
JOHN E. BLACK.
